UNITED STATES PATENT OFFICE.

JOHN F. A. HOORT, OF NEW YORK, N. Y., ASSIGNOR TO THE EAST ROCKFORD MANTEL COMPANY, OF ROCKFORD, ILLINOIS.

DESIGN FOR A MANTEL.

SPECIFICATION forming part of Design No. 24,209, dated April 16, 1895.

Application filed March 21, 1895. Serial No. 542,713. Term of patent 3½ years.

To all whom it may concern:

Be it known that I, JOHN F. A. HOORT, a citizen of the United States, residing at New York, in the county of New York and State 5 of New York, have invented and produced a new and original Design for Mantels; and I do hereby declare the following to be a full, clear, and exact description of the same, reference being had to the accompanying drawing, forming a part thereof.

The figure of the accompanying drawing is an isometric view of the new design for mantels.

The leading feature consists in the design 15 for a mantel comprising heavy lateral columns, two at each extremity of the mantel on opposite sides thereof and together extending nearly the whole height of the same, the upper columns supporting an entablature which 20 at its intermediate part is situated in the rear of the parts immediately surmounting the said columns.

Numeral 1 denotes the mantel shelf and 2 its supporting columns.

3 indicates the upper columns and 4 and 5 25 the front and rear portions of the entablature. This entablature and the mantel shelf extend nearly the entire width of the article and both the upper and the lower columns are larger than usual in this class of designs, the whole 30 effect being one of great solidity. Immediately above the panel opening 5 is a cornice 6.

The panel frame extends nearly the whole width of the mantel.

What I claim is—

The design for a mantel as shown and described. 35

In testimony whereof I affix my signature in presence of two witnesses.

JOHN F. A. HOORT.
